UNITED STATES PATENT OFFICE.

JOSEPH BOARDMAN CANN, OF BOSTON, MASSACHUSETTS.

IMPULSE-PUMP.

1,097,531.

Specification of Letters Patent. Patented May 19, 1914.

Application filed June 2, 1913. Serial No. 771,266.

To all whom it may concern:

Be it known that I, JOSEPH BOARDMAN CANN, a citizen of the United States, residing at Boston, in the county of Suffolk and 5 State of Massachusetts, have invented certain new and useful Improvements in Impulse-Pumps; and I do hereby declare the following to be a full, clear, and exact description of the invention, such as will enable others skilled in the art to which it 10 pertains to make and use the same.

This invention relates to pneumatic pumps, and as its principal object contemplates the provision of a device of the character set forth which may be readily applied to a cylinder of any four-cycle combustion engine and will quickly and efficiently inflate the tires of an automobile.

A further object of this invention is to 20 provide an air pump, applicable to the cylinder of an internal combustion engine, which will be operated by the impulse given by the compression of incoming gas entering the cylinder from the carburetor, mingled with 25 additional atmospheric air mechanically admitted to the cylinder, during the upward stroke of the engine.

A still further object is to construct the 30 pump with such regard to proportion, number and arrangement of parts that it may be cheaply manufactured, and will be durable and efficient in its operation.

The above and additional objects are accomplished by such means as are illustrated 35 in the accompanying drawings, described in the following specification, and then more particularly pointed out in the claims which are appended hereto and form a part of this application.

With reference to the drawings, wherein 40 I have illustrated the preferred embodiment of my invention as it is reduced to practice, and throughout the several views of which similar reference numerals designate corresponding parts: Figure 1 is a longitudinal section of the pump, illustrating the various parts in assembled relation; Fig. 2 is a top plan view; Fig. 3 is a vertical section taken 45 through the air inlet valve; and Fig. 4 is 50 a section on the line 4—4 of Fig. 3.

Proceeding now to the description of the drawings, the numeral 1 designates a preferably cylindrical outer casing, the lower terminal of which is exteriorly screw threaded 55 to receive the internally screw threaded annular flange 2 of a closure cap 3, centrally

of which is formed an internally screw threaded boss 4 adapted to receive a nipple to be screw threaded in the engine cylinder. By removing the spark plug of one cylinder of the engine, a nipple may be threaded in the spark plug opening and the member 4 applied, the pump casing being thus held in desired position on the cylinder. Within the casing 1 is arranged an inner casing 5 of smaller diameter and length than the member 1. The inner casing 5 is screw threaded externally at its upper end to receive the internally screw threaded annular flange 6 of a closure cap 7, the annular upwardly extending flange 8 of which is screw threaded into the upper end of the member 1 and bears against the closure plate 9 thereof. The member 9 carries a centrally disposed downwardly extending boss 10 cast with a vertically extending valve stem bore 11, and an enlarged bore or recess 12, this latter recess being adapted to receive the upper terminal of a spiral spring 13 mounted in encircling engagement on the valve stem 14 of a puppet valve 15. The valve 15 is of customary structure and is normally seated in the valve seat formed in the member 7, illustrated in Fig. 1. The inner casing 5 is communicant with the atmosphere through the air inlet 16 pipes 17.

Extending downwardly from the level of the air inlet 16 is a secondary inner casing 17 formed integrally with the member 5 and externally screw threaded to receive the internal annular lug 18 of a band wall 19 which in the assembled relation of the parts 18 and 7, extends in parallel spaced relation to the member 17 and acts as a receiving chamber for one terminal of a spiral spring 20, mounted in encircling engagement with a piston rod 21. The piston rod 21 is equipped at one terminal with a piston head 22 having the customary packing ring 23 and carries at its upper terminal a piston head 24 of less diameter than the member 22 and also equipped with a packing ring 25.

The member 22 is arranged for movement through the lower portion of the outer casing 1 while the member 24 is arranged for sliding movement through the inner casing 5. The spring 20 bears at one terminal against the piston edge 22 and at the other terminal against the member 18, being secured at each terminal by any suitable fastening means. This spring is of the expansion type and is adapted to normally hold

the piston head 23, in its lowermost position, in spaced relation to the member 3, as illustrated in Fig. 1.

It is desirable to emphasize the fact that 5 the spring 20 acts to hold the piston head 22 in spaced relation from the member 3, for it is readily apparent that were the piston head 22 to come in contact with the member 3 it would strike the closure cap with great 10 force on each down-stroke of the piston. It is also to be observed in this connection that the spring 20 is of such length and is of such resisting power that when compressed to a maximum limit on the up-stroke of the 15 piston rod 21, it will prevent the engagement of the piston head 24 with the member 7.

The chamber formed between the member 7 and the member 9 is provided with a coupling plate 26, internally screw threaded and adapted to receive an air hose 27. The chamber formed in the outer casing 1 below the member 7 is communicant with the atmosphere through openings 28 formed in the 25 wall of the casing 1 adjacent the upper end thereof.

It has been found after examination that when the gas engine is slowed down to its slowest running point, which will then give 30 very rapid pulsation in a pump of this nature, there will not be sufficient gas admitted through the throttle to completely fill the cylinder to which the pump is attached. Consequently the compression on the up- 35 ward stroke would be much less than it would be with the cylinder completely filled, so there has been added an auxiliary air inlet valve illustrated in detail in Fig. 3 and designated as an entirety by the numeral 40 29. This valve 29 is formed as a part of the cap 3, being preferably arranged, in practice, intermediate the length of the boss 4. In the preferred embodiment illustrated in detail in Fig. 3 the valve casing is formed 45 by two annular, laterally extending flanges 30 and 31, formed integrally with the member 4. The flange 30 is internally screw threaded to receive a closure plug 32 which is cored to produce a recess 33 and is centrally equipped with an annularly disposed ring 34, the ring 34 and recess 33 being provided for the obvious purpose of receiving the terminal of a valve stem 35. A valve head 36, substantially frusto-conical in 50 shape, is carried by the valve stem 35 and is normally held in closed position against a valve seat 37 by a helical spring 38, which is wound around the valve stem and bears at one terminal against the ring 34 and at the 55 other against the inner face of the member 36. The valve seat 37 is formed with a plurality of channels 39, which are four in number, in the preferred embodiment of this invention, as illustrated in detail in Fig. 4. 60 65 When as will be hereinafter more fully dis-

closed the air enters the valve inlet 40, upon the recession of the valve 36 from the valve seat 37, it passes around the valve through the channels 39. It is desirable to emphasize the fact that while the valve above described is preferably employed in connection with the impulse pump of this invention, any other desired and suitable type of puppet valve may be employed without impairing the efficiency of the pump.

The actual construction of the pump being thus disclosed, it now remains to describe the operation of the pump when applied to an engine cylinder. In this connection reference will be made to the lower 70 chamber of the outer casing 1 as chamber A, the chamber formed interiorly of the member 5 as chamber B, and the chamber formed between the members 7 and 9 as chamber C. After the nipple connecting the boss 4 has 75 been applied to the cylinder, in the manner above described, the engine is started, and as the best efficiency of the pump will be obtained with the engine running at its lowest point of throttle, sufficient gas will not be 80 admitted from the carburetor to fill the cylinder to its greatest density on the suction stroke, and there will be a partial vacuum within the cylinder which will be filled by atmospheric air forcing open the valve 85 and admitting a sufficient supply of air to completely fill the cylinder of the engine, which on the upstroke will compress against the head of the piston 22 carrying the member 22 upwardly and consequently pushing the piston 24 toward the member 7. The 90 chamber B being filled with air at atmospheric pressure, which has entered the casing 5 through the air inlet 16 previous to the upward movement of the member 24, 95 the air will be compressed as the piston head 24 approaches the upper portion of the casing 5. When the compression of the air in chamber B exceeds the pressure of the air in chamber C, it will tend to lift the valve 100 105 110 115 120 125 130 135 140 145 150 155 160 165 170 175 180 185 190 chamber A will exhaust through the openings 28, thus preventing the necessity of forcing the piston head 22 upwardly against air compression.

5 In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to when required, without sacrificing any of the advantages of my invention, as defined in the appended claims.

What is claimed is:—

1. An impulse pump, comprising an outer casing, an inner casing mounted within the outer casing in spaced relation to the side and end walls thereof, means for supporting the inner casing within the outer casing, and admitting atmospheric air thereto, a closure cap for the upper end of said inner casing, an annular downwardly extending flange on said cap engaging the sides of the inner casing, said cap having a valve seat centrally thereof communicating with the interior of the inner casing, an upwardly extending annular flange formed near the edge of said closure cap, engaging the inner side wall of the outer casing and upper end wall thereof and forming a chamber, a valve positioned within the chamber and engaging the valve seat in the cap, said chamber having a discharge opening therein, pistons operatively arranged within the inner and

outer casings, spring means for returning the pistons to operative position and the lower end of said outer casing provided with an opening therein adapted for communication with an engine cylinder, said outer casing having discharge openings adjacent its upper end.

2. An impulse pump comprising an outer casing, an inner casing positioned within the outer casing in spaced relation to the side and end walls thereof, a closure cap having a central valve opening therein, mounted upon the upper end of said inner casing, a downwardly extending annular flange on the closure cap engaging the sides of the inner casing, an upwardly extending peripheral flange on the cap, engaging the side and top walls of the outer casing and forming a chamber, a valve positioned within the chamber and engaging the valve opening in said cap, said chamber having a discharge opening in its side walls, means within the outer casing adapted to be operated by exhaust from an engine for forcing air through said inner casing into said chamber comprising pistons slidably mounted within the inner and outer casings, and spring means operatively connected with said pistons, said outer casing having discharge openings therein, and air intake pipes communicating with the inner casing and atmosphere.

In testimony whereof I affix my signature in presence of two witnesses.

JOSEPH BOARDMAN CANN.
